UNITED STATES PATENT OFFICE.

STOCKTON BATES, OF PHILADELPHIA, PENNSYLVANIA, ASSIGNOR TO THE BRIDESBURG MANUFACTURING COMPANY, OF SAME PLACE.

FEED-GUIDE FOR CARDING-MACHINES.

SPECIFICATION forming part of Letters Patent No. 389,133, dated September 4, 1888.

Application filed December 1, 1887. Serial No. 256,692. (No model.)

To all whom it may concern:

Be it known that I, STOCKTON BATES, a citizen of the United States, residing at Philadelphia, in the county of Philadelphia and State 5 of Pennsylvania, have invented certain new and useful Improvements in Feed-Guides for Carding-Machines; and I do hereby declare the following to be a full, clear, and exact description of the invention, such as will enable 10 others skilled in the art to which it appertains to make and use the same.

My invention consists in an improved guide through which the wool in the shape of slivers is directed into the feed-rollers of a carding-machine, said guide comprising a perforated bar to which conducting-tubes are attached and arranged in divergent rows radiating from the meeting line or bite of the introductory feed-rollers of the carding-machine, 15 as will be hereinafter described and claimed.

The object of my invention is to prevent the slivers from coming in contact with one another, and thereby obstructing the passage to the feed-rollers, as in the case of guides of ordinary construction.

In the accompanying drawings, Figure 1 is a perspective view of my improved feed-guide. Fig. 2 is a rear elevation of the same. Fig. 3 is a transverse section in the line $x-x$ of Fig. 30 2, showing also the introductory rolls of a carding-machine. Fig. 4 is an outline side view of a sliver-creel and of a front part of a carding-machine provided with my invention. Fig. 5 is an outline top view of the same.

The letter A in the drawings represents an ordinary sliver-creel, B a carding-machine, and C my improved guide.

The creel A holds the sliver-balls, a, delivered by carding-machines of a previous coarser 40 class. The number of sliver-balls in a creel varies between forty-eight and one hundred and twenty, (more or less,) and the said sliver-balls being of considerable size, they, when mounted in the creel for unwinding, occupy 45 a great deal of room vertically and horizontally, and the slivers a' unwound from said balls are drawn at different angles toward the feed-rollers b b of the carding-machine, as seen in Figs. 3, 4, and 5.

In front of the feed-rollers my feed-guide C is suitably attached to the frame of the card-

ing-machine. It is composed of a bar, c, having rows c' c' of guide-tubes D, through which the slivers pass. I have shown only two distinct rows, which form four distinct rows of receiving-mouths; but they may be arranged in more or less rows, to suit requirements. These rows diverge, as shown, toward the creel, so as to receive the slivers a' at safe distances from one another, and the tubes which form 55 the middle rows of receiving-mouths are longer than those which form the upper and lower rows of receiving-mouths. All of the tubes of one row enter the bar c on the same line, and this line is parallel with the horizontal edges 60 of the bar, thus increasing the distance between the receiving-mouths of the tubes into which the slivers a' pass from the creel to the carding-cylinder. The tubes, by being deflected as described and shown, have enough 65 space between them at their receiving mouths to prevent the loose fibers of contiguous slivers in their passage to the tubes from the creel coming together, and those of one sliver from catching upon those of another, and thus causing 70 entanglement, breakage, and loss of time, with diminution of product in a given period. The described arrangement of the tubes also permits of the delivery ends of the tubes being 75 arranged so close together that in a comparatively small compass as many as, say, seventy-two slivers (more or less) can be introduced to an ordinary-sized carding-surface without danger of the loose fibers of one sliver becoming entangled with those of a contiguous sliver 80 at points between the creel and the tubes; whereas with the common construction it is not regarded practicable to present more than forty-eight "ends" or slivers to a like-sized carding-surface as that which I employ for 85 seventy-two ends or slivers, because there is not space enough left between the slivers in their passage from the creel to the points where they enter receiving-passages arranged in the common way, while insuring their delivery directly to the introductory feed-rolls. The tubes at their mouths are formed with 90 smooth beads d, which are rounded off on their inner sides, as well as on their outer, and through which the slivers glide without undue 95 friction. The delivery-end portions d' of the 100 two rows of tubes illustrated are inserted into

holes c^2 of the bar c , said holes radiating from the meeting line or bite of the feed-rolls. The holes are of slightly-tapering form, so that the tubes can be easily inserted into or removed therefrom by hand in case short tubes are to be exchanged for long ones, or vice versa.

The guides in some cases, as heretofore used, consist of iron combs similar to reeds in the battens of looms, between the teeth of which

10 the slivers pass toward the feed-rollers of the carding-machine. These teeth are very closely arranged, and the slivers pass through them in very close proximity to one another, the fuzzy structure of the same frequently causing

15 two or more to combine and unite before their arrival at the guide, and thus clog said guide and become torn, so as to disturb the uniform feed of the machine. Efforts made with a bar perforated simply with round holes have

20 proved as futile as those with the comb for the same reason; but with the aid of the diverging tubes D , arranged on a bar, c , placed close to the feed-rolls, the approaching slivers can be kept at such distances from one another be-

25 tween the creel and the guides and delivered so close to the feed-rolls that, no matter how loose or fuzzy they may be, they cannot unite before they arrive between the feed-rollers, and thus a uniform and uninterrupted feed to

30 the carding-machine is secured.

It will be seen from the foregoing description and accompanying drawings that the improved guide C can be placed close up to the introductory feed-rolls b of the carding-machine, and

35 that the tubes D and the holes c^2 are so arranged in vertically-radiating rows that the slivers are kept separate from each other between the creel and the guide C , and are conducted by the guide-tubes D and holes c^2 almost imme-

40 diately between the said feed-rolls. It will also be seen that while the delivery ends of both the longer and shorter rows of tubes on either side of the longitudinal meeting line of the feed-rolls enter holes c^2 radially from the

bite of the feed-rolls and on a line which is 45 straight, the outer or receiving ends of these rows of tubes are on a zigzag line on account of their being divergent on different angles, and said zigzag line is also undulating on account of the tubes, whether radiating upward 50 or downward with respect to the meeting line or bite of the feed-rolls, being made of different lengths, as shown.

What I claim is—

1. In combination with feed-rolls of a card- 55 ing-machine, the guide C , provided with tubes D , arranged in rows radiating from the meeting line or bite of said feed-rolls, substantially as described.

2. In combination with the feed-rolls of a 5c carding-machine, the guide C , consisting of a bar, c , having holes c^2 , and tubes D , of different lengths, radiating on different angles from the meeting line or bite of the said feed-rolls, substantially as described.

3. In combination with the feed-rolls of a carding-machine, the removable interchangeable divergent tubes D , made of taper form, in combination with the bar c , having tapered holes c^2 , radiating from the bite of the said feed-rolls, substantially as and for the purpose described.

4. The bar c , provided with tubes D , ar- 75 ranged in rows c^2 , the delivery ends of which enter the holes in the bar on straight lines, while their mouths form zigzag lines, substan-

tially as described.

In testimony whereof I affix my signature in presence of two witnesses.

STOCKTON BATES.
